UNITED STATES PATENT OFFICE.

ISAAC DE KAISER, OF WILKINSBURG, PENNSYLVANIA.

GOLF-TEE.

1,248,826.

Specification of Letters Patent.

Patented Dec. 4, 1917.

Application filed October 6, 1916. Serial No. 124,044.

To all whom it may concern:

Be it known that I, ISAAC DE KAISER, a citizen of the United States, and a resident of Wilkinsburg, in the county of Allegheny 5 and State of Pennsylvania, have invented a new and useful Improvement in Golf-Tees, of which the following is a specification.

My invention relates to golf tees and particularly to such devices as are adapted for 10 continued use.

My invention has for one of its objects to provide a device of the character indicated above that is movably mounted and automatic in operation to return to its initial 15 position upon its being actuated therefrom.

A second object of my invention is to provide a golf tee that is permanent in form, durable in construction and efficient in operation to support golf balls without offering 20 obstruction to the strokes of players.

It is well known that the present methods of forming tees or supports for golf balls for driving from the teeing grounds are very unsatisfactory. It is necessary to form 25 the tees manually from wet sand, a supply of water and of sand being kept on each teeing ground for that purpose. Such methods have a number of disadvantages both from the standpoint of the player and from that 30 of the golf club.

The hands of the player are soiled by handling the materials for making the tees. It is practically impossible to construct tees 35 of uniform height and a slight difference in that regard may cause a poor drive or a "foozle". In cold weather, the handling of the wet materials causes discomfort. In case of freezing temperatures, the inconvenience and impracticability of the usual 40 arrangement are obvious.

The use of sand and water necessitates that a supply of these materials be kept on each teeing ground, a considerable amount of time and labor being expended for this 45 purpose. In case the grounds are covered with clay, the use of sand causes the surfaces to be disagreeably loose and dusty. If a grass surface is employed, the sand injures the grass and thus damages both the appearance and the playing surface of the teeing 50 grounds.

It has been proposed, heretofore, to provide tees ready for use and these may be of such material as to retain their form after 55 being used. Such devices are inconvenient, however, for it is either necessary to re-

trieve them for the succeeding drive or to carry a supply of them for use throughout the course.

I provide an arrangement by means of 60 which all of the above described inconveniences may be avoided. A tee of the desired height is mounted on each of the driving greens and it may remain in any desired spot as long as desired. The ball-supporting member is arranged in the form of 65 a pendulum and is adapted to move readily out of the path of movement of the player's club when actuated, in order not to interfere with the stroke. The pendulum member operates to automatically return to an 70 operative position after a ball has been driven from it, for the succeeding drive.

In the accompanying drawings, Figure 1 is a top plan view of a device constructed in 75 accordance with my invention. Fig. 2 is a view, in side elevation, of the device of Fig. 1, a golf ball being shown in operative relation. Figs. 3 and 4 are views respectively in top plan and side elevation of the pendulum or ball-supporting member. Fig. 5 is a view, partially in elevation and partially in section, of the ball-supporting member, taken at right angles to Fig. 4. Figs. 6 and 80 7 are respectively end and side views of the 85 weight constituting a part of the pendulum member. Figs. 8, 9 and 10 are respectively top, side and bottom views of one of the casing members. Fig. 11 is a view, in longitudinal section, of the device mounted in 90 position for actual use, the pendulum member being shown in a position assumed upon its being actuated.

A casing 1 or housing, of substantially 95 rectangular shape, is composed of two parts 2 and 3, that are held together by stud bolts or screws 4. The part 2 is illustrated in Figs. 8, 9 and 10. The part 3 corresponds to part 2. Each of the casing members is provided with an integral flange 5 which extends at right angles from the side and in each direction from the ends of the casing member. The flanges together present a plane surface of comparatively large area. The casing members may be of brass, iron or 100 other suitable material. Each of the flanges 5 is provided with a rectangular notch 6.

Each of the casing members is provided with a groove 7 extending downwardly from the notch 6, the upper end of the groove being open. The lower ends of the grooves 110 constitute bearing members for pivotally

supporting a pendulum-like member 8, the upper end of which projects through the rectangular slot formed by the notches 6 and above the plane of the flanges 5. The bottom of the casing or housing 1 is open for a purpose to be later described.

The pendulum member 8, which is illustrated in Figs. 3, 4 and 5, consists of a body portion 9 that is substantially square in cross section. An enlarged lower portion 10 is arranged in the form of a ring to inclose and support a weight 11 of brass, lead or other suitable material. As shown in Fig. 7, the weight 11 is provided with a circumferential groove 12.

The upper portion 13 of the pendulum member 8 is tapered to have substantially the form of a square pyramid, the top portion having a concave recess 14 for receiving 20 a golf ball. The member 8 is supported in the grooves 7 by a short shaft 15 having a knurled portion indicated at 16. The member 8, which is preferably of rubber, composition, or other suitable flexible material, is 25 constructed by molding, the grooved weight 11 and the knurled shaft 15 being properly positioned in the mold previously. The result is practically an integral structure.

The upper surface of the flanges 5 is covered by a plate 17 of rubber, fiber, composition or other suitable material having the characteristics of being waterproof and of durability. The cover plate 17 is provided with a rectangular slot 18 that coincides 35 with the slot formed by the notches 6.

When the several parts occupy their normal positions as shown in Fig. 2, it will be noted that the tapered portion 13 of the member 8 projects above the surface of the 40 plate 17 and is adjacent to one end of the slot 18. In practice, the length of the projecting portion 13, which corresponds to the usual tee, and which, for convenience, may be designated as such, is arranged to meet 45 the particular requirements of the users, one-half inch being the usual standard length. This height may, however, be varied by substituting a pendulum member having any desired dimensions.

50 The device is mounted with the upper surface of the plate 17 substantially flush with the surface of the teeing ground, as shown in Fig. 11. The mechanism is so positioned relatively to the course that its 55 longitudinal axis is in substantial alinement with the direction in which the ball is to be driven, the unoccupied portion of the slot 18 being placed forwardly in order that the tee 12 may be free to move in the direction of 60 the stroke.

In the operation of the device above described, a ball 19 is placed in the concave recess 14 of the tee 13, as shown in Fig. 2. The weight of the bottom portion of the 65 pendulum member 8 is sufficient to prevent

the weight of the ball from rendering the supporting means unstable. The player makes his stroke in the usual manner.

If the height of the stroke has been properly gaged, the club does not strike the tee 70 and the latter is practically undisturbed. If, however, the club strikes sufficiently low that the tee is engaged by it, the latter yields readily both by reason of its flexibility and its pivotal mounting. The tee recedes momentarily into the rectangular recess, the pendulum assuming approximately the position illustrated in Fig. 11 and indicated by dotted lines in Fig. 2.

The pendulum is at once restored to its 80 normal upright position by force of gravity. The adjacent end of the slot acts as a stop to prevent oscillation of the tee beyond its operative position. The tee is then ready for the drive of the succeeding player.

85 While my invention is intended for use in connection with the usual play on a golf course, it is of particular value when used in making practice strokes in driving. It is also of great assistance to the so-called "professional" or instructor during the process of teaching the art of driving to a novice. It will be readily understood that the operation of constructing a tee for each stroke under the above conditions becomes a burdensome labor, and, in addition, much valuable time is consumed.

90 The device is arranged to permit such water as may enter the casing or housing to escape through the opening in the bottom. 100 By reason of the fact that the body portion is of relatively small dimensions, the device may be readily shifted from one point on the teeing ground to another, as desired.

95 The various materials employed are such as possess qualities of durability and are substantially unaffected by continuous exposure to the elements. Many modifications will occur to those skilled in the art to which my invention appertains and it is understood 105 that such changes may be made as fall within the scope of the appended claims, without departing from the spirit of my invention.

110 I claim as my invention:

115 1. In a golf tee, the combination with a casing comprising side portions having vertically-extending grooves therein, said casing having a horizontally-extending slot, of a pendulum-like ball-supporting member 120 having a pin extending into said grooves to form a pivotal support for said member above its center of gravity whereby it has a normal upright position in which it projects through said slot and adjacent to one 125 end of the latter.

120 2. In a golf tee, the combination with a member having a horizontally-extending surface, of a ball-supporting member pivotally supported thereby having a normal 130

- position in which it projects vertically beyond said surface and an abnormal position in which the projecting portion is at least partially below said surface, said ball-supporting member being so constructed as to return automatically to its normal position, and means for preventing the return of said member beyond its normal position.
3. In a golf tee, the combination with a stationary housing having an opening in its upper surface, of a ball-supporting member pivotally supported by said housing and normally projecting through said opening, said member receding into said opening upon being actuated and having the inherent characteristic of automatically returning to its normal position adjacent to one end of said opening which constitutes a stop for said member.
4. In a golf tee, the combination with a housing, of a ball-supporting member pivotally mounted therein having a normal position in which it projects therefrom, said member being provided with a supporting shaft, a weight member and a body portion

of material molded around the shaft and weight member to form a substantially integral structure.

5. In a golf tee, the combination with a housing, of a ball-supporting member pivotally mounted therein having a normal position in which it projects therefrom, said member being provided with a recess for receiving a ball and comprising a supporting shaft, a weighted portion below said shaft and a body portion of flexible material.

6. In a golf tee, the combination with a casing member having a flange member at least a portion of which is adapted to be placed substantially flush with the surrounding surface, said casing member having a slot therein, of a ball-supporting member freely suspended therein and so arranged as to automatically return to its operative position.

In testimony whereof, I have hereunto subscribed my name this 5th day of October, 1916.

ISAAC DE KAISER.
